Primary Examiner — Mary Ann Calabrese*Assistant Examiner* — Jennifer L Rempfer*(74) Attorney, Agent, or Firm* — Sughrue Mion, PLLC(57) **CLAIM**

The ornamental design for an electronic device, as shown and described.

DESCRIPTION

FIG. 1 is a top front perspective view of an electronic device showing our new design;
FIG. 2 is a front elevational view thereof;
FIG. 3 is a rear elevational view thereof;
FIG. 4 is a left side elevational view thereof;
FIG. 5 is a right side elevational view thereof;
FIG. 6 is a top plan view thereof;
FIG. 7 is a bottom plan view thereof;
FIG. 8 is an additional top front perspective view thereof with the electronic device shown at a different direction from that of FIG. 1; and,
FIG. 9 is an additional top front perspective view thereof with a portion of the band shown partially truncated.
The broken lines in the drawings represent portions of the electronic device that form no part of the claimed design. The dash-dot-dash lines represent a symbolic break boundary of the band portion of the electronic device and form no part of the claimed design.
